UNITED STATES PATENT OFFICE.

CHARLES J. SOLI, OF RACINE, WISCONSIN.

PANE-FASTENER.

1,385,725.

Specification of Letters Patent. Patented July 26, 1921.

Application filed August 8, 1919. Serial No. 316,150.

To all whom it may concern:

Be it known that I, CHARLES J. SOLI, a citizen of the United States, and resident of Racine, in the county of Racine and State of Wisconsin, have invented certain new and useful Improvements in Pane-Fasteners; and I do hereby declare that the following is a full, clear, and exact description thereof.

My invention pertains to new and useful improvements in means for securing panes of glass or the like in conventional types of window or other sashes.

The primary object of the present invention is to improve upon the present forms of securing means now in use, such as is illustrated in my Patent No. 1,217,356, granted Feb. 27, 1917. In carrying out this provision is made for a combined covering and retaining strip for the glass receiving groove of the lower sash rail, thereby not only holding the glass in position but also protecting said lower rail against the usual rotting action set up by water settling in said groove.

With these general objects in view the invention resides in the novel features of construction, combination and arrangement of parts which will be hereinafter described and claimed and shown in the drawing wherein—

Figure 1 represents a vertical transverse sectional view through a window sash and frame, the former being in closed position.

Fig. 2 is a similar view of the frame with the sash in open position, the same being shown in elevation.

In the accompanying drawing, wherein similar reference characters designate like parts in both of the views, 1 indicates a window frame of conventional design in which a window sash 2 is hinged along one vertical edge as shown at 3. The sash 2 consists of a frame of usual shape, the opening of which is normally covered by a pane 4 of glass 4 the inner edges of the top, bottom, and side rails of the sash being rabbeted as is customary, the rabbet in the bottom rail 5 providing a shoulder 6.

The top and side portions of the pane 4 are secured in the rabbets of the adjacent parts of the sash by means of beading 7, whereas the bottom portion thereof is retained by my improved metallic protecting member 8. This member is of a length sufficient to extend between the side rail of the

sash and is provided with a channel 9 receiving the edge portion of the pane 4, the inner flange 10 thereof being seated against said shoulder 6. The outer flange 11 is of double thickness and has sufficient spring 60 to compensate for the movement of the pane 4 due to expansion and contraction, etc.

The retaining member is preferably formed of relatively light gage sheet metal which can be readily stamped into shape. 65 The inner flange 10 of the channel of the member has a protective strip 12 extended laterally from its free edge to overlie the portion of the lower sash rail inwardly of said shoulder 6. Inasmuch as this portion 70 of the rail is slightly downwardly and inwardly inclined as shown in Fig. 1, the protective strip assumes a similar inclination.

The top surface of the lower sash rail 5 outwardly of the shoulder 6 being lower 75 than that part of the rail covered by the strip 12, the outer protective strip 13 extends laterally from the flange 11 substantially in the plane of the base of the channel 9, and is slightly downwardly inclined to 80 provide a water shed. As clearly shown in Fig. 1 the strip 13 is readily formed as a continuation of the flange 11 by bending the portion of the member 8 adjacent the channel 9 upon itself, thereby forming the 85 double thickness flange 11 as above mentioned.

Possibility of water creeping beneath the protective strip is obviated by a hook-like tongue 14 which is formed on the free edge 90 of said strip 13 and depends therefrom. One portion of the tongue is extended inwardly and substantially parallel to the strip 13, and is seated in a groove cut in the outer side of the lower sash rail 5. The 95 outer corner of the lower rail is thereby fully protected against any possibility of moisture reaching the same.

In assembling the pane of glass 4 in a sash having one of my improved retaining members 8 on its lower rail, the lower edge of said pane is seated in the channel 9 of the member and then the side and top edge portions of the pane are brought into engagement with the shoulders formed on the 100 other rails. After the strips of beading 7 have been secured in place the pane will be 105 securely held in the sash. It will be noted that said shoulders on the top and side rails of the sash 2 are faced inwardly, whereas 110

the shoulder 6 faces outwardly. Thus the first mentioned shoulders prevent water from leaking around the edges of the pane, whereas the retaining member 8 sheds any water which may tend to accumulate on the lower sash rail 5. However, if it is considered necessary or advisable, the combined retaining and protective member 8 may be placed around all of the edges of the pane 10 and disposed in engagement with the side and top rails of the sash.

From the foregoing description taken in connection with the accompanying drawing, it will be appreciated that a window-pane, 15 may be readily inserted from the inside of a room without the necessity of removing the sash from the window-frame, thus greatly eliminating the inconveniences and costs incident to replacing panes in the ordinary window-frames. This advantage, it will be seen, is obtained by having the shoulders at the sides and top of the frame, against which the pane seats, faced inwardly, the

retaining beading strips 7 being positioned interiorly of the frame. 25

I claim:

The combination of a frame having certain of its rails rabbeted to form shoulders facing in one direction and another of its rails rabbeted to form a shoulder facing in the opposite direction, said last named rail having a covering strip of sheet metal comprising a channel portion seated in said rabbet, the metal at one edge of the channel being extended to cover the shoulder formed by said rabbet, the metal at the other edge of the channel being bent upon itself to form a wall of double thickness for that side of the channel and being bent outwardly at the base of the wall, and a lip on the outer edge of 30 said strip extending into the side of said rail. 35

In testimony that I claim the foregoing I have hereunto set my hand at Milwaukee, in the county of Milwaukee and State of Wisconsin. 40

CHARLES J. SOLI.
